UNITED STATES PATENT OFFICE

ERNEST W. CLARK, OF SCHENECTADY, NEW YORK, ASSIGNOR TO GENERAL ELECTRIC COMPANY, A CORPORATION OF NEW YORK

HIGH-TENSION ELECTRIC CABLE

Application filed July 16, 1929. Serial No. 378,777.

The present invention relates to high tension electric cables of the type in which the conductor is insulated by a substance permeable to oil as wrapped-on paper for example, and has a channel for the oil and an outside sheath of lead for example.

The object of my invention is to provide a cable of improved construction, and specifically my invention is directed to the construction and arrangement of the parts which form a channel or channels for the oil used in permeating the insulation.

For a consideration of what I believe to be novel and my invention attention is directed to the accompanying specifications and the claims appended thereto.

Fig. 1 is a view partly in elevation of a piece of high tension electric cable; Fig. 2 is a perspective view of the strip used in forming the oil channel; Fig. 3 is a section taken on line 3—3 of Fig. 1, and Figs. 4 and 5 are modified forms of the strip.

6 indicates an electric conductor which is surrounded by a body of insulation 7 which is commonly made of strips or ribbons of paper and tightly wound thereon, the joints between strips in the various layers overlapping. Surrounding the insulation and separated herefrom by a space is a lead or equivalent sheath 8.

In order to form an oil channel which extends annularly and longitudinally of the cable there is tightly and spirally wound over the insulation a thin metal tape or strip 9. The strip is provided with a large number of small individual projections 10, some of which are on the side of the strip adjacent to the insulation and the others are on the outside of the strip and engage the inner wall of the sheath. These projections both inside and outside of the strip or tape 9 hold the parts in concentric relation and also form an annular channel 11 for the oil, said projections extending radially when the strip is in place. The oil permeates the insulation and so completely fills the channel. In order to insure the complete filling of the channel all times suitable reservoirs may be provided at intervals along the length of the cable in a manner that is well understood.

By providing numerous small projections on the metal strip or ribbon the latter can be smoothly and evenly wound over the insulation and the outer projections afford a good seat for the lead sheath. The turns or convolutions of the strip may be separated by a small clearance 12 so that the oil can freely enter the paper in the region thereof. 55

The projections on the tape, or strip may be on both sides thereof or only on one side 60 as shown in Figs. 4 and 5. Where the projections are provided on both sides there is formed what amounts to two concentric oil channels, one between the tape or strip and the insulation and the other between the tape 65 or strip and the inner wall of the sheath as best shown in Fig. 3. By making the projections numerous and with suitable spaces between them the construction offers very little resistance to the flow of oil both when 70 the cable is being impregnated in the factory and after it is put in service.

Since the projections 10, whether on one or both sides of the strip, can be made by passing the strip through suitable matched rollers having projections and indentations, the said strips are cheap to manufacture and with the sheath form a simple and effective oil channel. The projections are preferably made without sharp corners or rough edges 80 of any kind.

The construction shown in Fig. 5 is somewhat simpler to make than the constructions previously described. In this case the strip 9 is made of thin copper, say of the order of 85 5 to 10 mils in thickness and 1" wide and the projections are spherical in form and project above the plane of the strip, say of the order of $\frac{1}{16}$ of an inch. The projections in this case, as well as in the case of Fig. 2, 90 are staggered. By using these well rounded projections it is a simpler operation to wind in the strip or tape than with the other forms as there is less chance of the projections catching during the winding operation. Where 95 the ribbon is made thin, as it naturally would be, in order to reduce the cost the projections should not extend quite to the edges of the strip, because if they did there would be more likelihood of the edges of the strip tear. 100

ing while being wound in place under considerable tension. The strips shown in Figs. 4 and 5 may be wound with the projections extending outwardly or inwardly as desired.

5 It is preferable, however, to have the projections on the outer surface thereby, avoiding denting the insulation and at the same time affording a good seat for the sheath.

I claim:

- 10 1. In an oil filled electric cable, the combination of a conductor, insulation thereon, an enclosing sheath, and a strip having a plurality of small individual projections thereon, said strip being located between the insulation and the inner wall of the sheath and defining therewith an annular oil channel.
- 15 2. In an oil filled electric cable, the combination of a conductor, insulation thereon, an enclosing sheath, and a spirally wound metal strip which is supported by the insulation and has a plurality of small outwardly extending projections thereon which engage the inner wall of the sheath and define between it and the body of the strip an annular oil channel.
- 20 3. In an oil filled electric cable, the combination of a conductor, permeable insulation thereon, a metal sheath, and a strip of metal which is spirally wound on the insulation and has a large number of individually formed
- 25 30 projections which engage the inner wall of the sheath and support the same and also cooperate with the sheath to define an annular oil channel.
- 35 4. In an oil filled electric cable, the combination of a conductor, permeable insulation thereon, a sheath and a strip of metal which is tightly wound over the insulation and under the sheath, and said strip having a large number of small projections on one
- 40 45 side thereof and in staggered relation, the projections and inner wall of the sheath defining an annular and longitudinally extending oil channel.
- 50 5. In an oil filled electric cable, the combination of a conductor, permeable insulation thereon, a metal sheath, and a thin strip of metal having a large number of individual projections on one side only, said strip being mounted on the insulation with the projections extending outwardly to form a seat for the sheath and defining therewith an annular oil channel.

In witness whereof, I have hereunto set my hand this 15th day of July, 1929.

ERNEST W. CLARK.
